UNITED STATES PATENT OFFICE

EMIL MUNDORF, OF AACHEN, GERMANY

WASHING AND FULLING OF FABRICS

Application filed November 22, 1928, Serial No. 321,195, and in Germany November 26, 1927.

The washing and fulling of fabrics is usually carried out nowadays by sewing some pieces of fabric together at their ends and passing them as an endless band, mostly in the form of a rope, between the rollers of the washing and fulling machine in the direction of the warp threads. During this treatment the warp threads are more or less stretched by the action of the own weight of the fabric rope and the pressure of the rollers, while practically no strain is exerted on the weft threads. In consequence thereof the fabric does not shrink at all or only little in the direction of the warp 10 or length of the fabric but often lengthens even, while it shrinks in the direction of the weft or width of the fabric by about 20 per cent. Now, during the treatments preceding the washing and fulling, especially 15 during the weaving itself, the warp threads have already been under a considerable strain too, while the weft threads are always more or less relaxed. These differences in the tension of the fabric threads 20 are not only not compensated for by the known washing and fulling methods but they are even aggravated, since there occurs during the same a considerable relaxation 25 of the weft threads but no relaxation of the warp threads, as stated above.

This unequal relaxation of the two systems of threads is a great disadvantage. Such fabrics are liable to crumple and difficult to iron, and the garments made thereof 30 will soon wear out and lose their smooth form and good fit in wearing.

The invention has for its object to provide a method of washing and fulling fabrics by which the above said disadvantage is avoided, this object being attained by passing the fabrics through between the washing and fulling rollers in the direction of the weft. The invention may be carried into effect by forming the usual endless band or rope from 40 a number of pieces of fabric of any desired

length which are sewn to one another at their selvedges so that the weft threads will extend in the longitudinal and the warp threads in the transverse direction of the band or rope. During the passage of such a rope between the washing and fulling rollers the weft threads are held under strain and the shrinking of the same is more or less prevented. In this way the inequality of relaxation of the two systems of threads otherwise entailed in the washing and fulling is avoided. Fabrics thus treated have a better finish. They are weatherproof and the garments made thereof retain their good form and are resistive against wear.

The accompanying drawing shows a diagrammatic plan view of a portion of a fabric band or rope made in accordance with the invention.

The band or rope to be passed through the washing and fulling machine is formed from a number of fabric pieces *a* which may have the usual length or shorter lengths obtained by dividing a piece of the ordinary length into shorter pieces. The fabric pieces *a* are sewn to one another at the selvedges or lists. *b* are the warp threads which extend in the transverse direction and *c* the weft threads which extend in the longitudinal direction of the band. The band or rope 50 is passed through between the rollers of the washing and fulling machine in the direction of the arrow *x*, i. e. in the direction of the weft threads of the fabric. The washing and fulling machines may be of well-known construction.

Having thus described my invention, what I claim as new and desire to secure by Letters Patent, is:—

1. The method of washing and fulling fabrics as a finishing operation in their manufacture which consists in passing the fabrics between the washing and fulling rollers in the direction of the weft of the fabric.
2. The method of washing and fulling

fabrics as a finishing operation in their manufacture which consists in sewing a number of pieces of fabric to one another at their selvedges so as to produce a band of fabric in which the weft threads extend in the longitudinal and the warp threads in the transverse direction and passing this band between the rollers of a washing and fulling machine in the direction of the weft threads.

10 In testimony whereof I have signed my name to this specification.

EMIL MUNDORF.
